Matthew McCready.

UNITED STATES PATENT OFFICE.

FREDERICK M. FURBER, OF REVERE, MASSACHUSETTS; SAMUEL R. CUTLER, OF REVERE, MASSACHUSETTS, ADMINISTRATOR OF SAID FREDERICK M. FURBER, DECEASED, ASSIGNOR TO CHARLES A. PIPENHAGEN, OF CHICAGO, ILLINOIS, AND JAMES F. RALEIGH, OF RIVER FOREST, ILLINOIS.

TEMPERATURE-CONTROLLING APPARATUS FOR INTERNAL-COMBUSTION ENGINES.

Application filed February 16, 1918. Serial No. 217,689.

Internal combustion engines are always equipped with some kind of a heat radiating system designed to dissipate the excessive heat developed in the engine cylinders and thus maintain the engine at a temperature at which it can operate efficiently. It is now a common practice to equip the internal combustion engines used in motor vehicles with a mechanism for regulating the heat dissipating action of the heat radiating system. In some instances this mechanism is arranged to be adjusted by hand but more frequently it is adjusted automatically by a thermostat which is so arranged as to be responsive to changes in the engine temperature. Mechanisms of this character are used not only for the purpose of maintaining the engine at substantially the temperature at which it can operate most efficiently, but also for the purpose of preventing the circulating liquid in the water cooling type of heat radiating system from freezing in excessively cold weather.

The present invention is especially concerned with the heat radiating system of the character just described, that is, those equipped with some means for controlling or varying the cooling action of the system, and the invention aims particularly to improve the control of the heat radiating action of these systems and to make this control more automatic.

Other objects of the invention and the manner in which it is proposed to accomplish them will be readily understood from the following description when read in connection with the accompanying drawings, in which:

Figure 1 is a side elevation, partly in cross section, showing one embodiment of the invention;

Fig. 2 is a vertical cross sectional view showing, on a larger scale, certain parts of the apparatus shown in Fig. 1; and

Fig. 3 is a side elevation showing a different embodiment of the invention.

The drawings show an internal combustion engine 2 of a type commonly used in motor vehicles and a water cooling system for said engine which comprises a radiator 4, a connection 6 leading from the upper end of the engine jacket to the upper part of the

radiator, and another connection 8 leading from the lower end of the radiator to the lower part of the water jacket. The arrangement shown is of the thermo-siphon system, although it will be understood that the invention is equally adapted to a pump system. In the normal operation of the apparatus the hot water leaving the upper end of the engine jacket passes through the connection 6 into the upper end of the radiator and flows downwardly through the radiator, where it is cooled, and then returns again through the connection 8 to the jacket. During the descent of the water through the radiator 4 a large proportion of its heat is dissipated to the air that is forced through the radiator, partly by the motion of the vehicle, and more particularly by the action of a fan (not shown).

The adjustable means above referred to for controlling the heat radiating action of the system comprises a series of shutters 10 mounted in front of the radiator frame or casing and arranged to swing about horizontal pivots 12 into either an open position, as shown in Fig. 2, a closed position, as shown in Fig. 1, or any intermediate position. In order to operate or adjust the shutters, a thermostat 14 is mounted in a suitable casing 16 that is located in a chamber at the upper end of the radiator, and a connection is provided between this thermostat and the shutters whereby the thermostat is enabled to close or open the shutters more or less, depending upon the temperature of the engine. These connections comprise a lever 18 pivoted in the radiator casing at 20 and a link 22 connecting one end of this lever with an arm 24 that projects from one of the shutters. All the shutters are pivoted to a common rod 26 so that they are obliged to move about their pivots in unison. A spring 28 connected at one end of the lever 18 and at its opposite end to the radiator casing tends to hold the shutters constantly in their closed positions and thus to cut off the flow of the air through the radiator and thereby reduce to a minimum the cooling or heat radiating action of the water cooling system. As the temperature of the engine rises and thus heats up the water in the circulating system, the thermostat 14 expands and

acts through its connections with the lever 18 to move the lever against the tension of the spring 28 in a direction to open the shutters, the extent of this opening movement 5 obviously depending upon the degree of the rise in temperature.

The mechanism so far described is in common use and is, in all essential particulars, substantially like that disclosed in my prior 10 Patent No. 1,114,246, granted October 20, 1914.

It will now be understood that when a motor vehicle equipped with an apparatus of the character above described has been operated for some time so that the engine has become thoroughly warmed up, the shutters will be partly or entirely opened by the automatic temperature responsive mechanism. If now the engine is stopped and the car is 20 left standing in an exposed location the water in the radiator will cool off rapidly and after a time the shutters will be closed automatically; but if the vehicle is left standing for any great length of time or 25 the weather is unusually severe the temperature of the water will be reduced to such a point that it will increase the difficulty of starting the engine, and it may even be reduced so far as to result in freezing the 30 water in the radiator. The present invention therefore provides means that operates upon the stopping of the engine to reduce the cooling action of the heat radiating system substantially to a minimum and thus 35 conserve the heat stored in the system. The danger of freezing the water in the circulating system or of reducing the temperature to an undesirable extent therefore is very 40 greatly reduced.

45 In the arrangement shown in Figs. 1 and 2, the connection between the thermostat 14 and the lever 18 comprises a rod 30, connected fast to the lower end of the thermostat (which in the arrangement shown is of the bellows type), a cylinder 32 mounted fast on the lower end of said rod, a piston 34 slideable freely in said cylinder, and a rod 36 fast on said piston and having a pin and slot connection with one end of the lever 18. The lower end of the cylinder 32 is threaded into a cylinder head or fitting 38 which is provided with a duct 40 leading from a point below the piston 34 and communicating with a flexible tube or pipe 42 that leads from the cylinder head to the intake manifold 44 of the engine 2. A hole 45 is drilled through the cylinder 32 at a point above the piston 34. As it is well understood by those skilled in this art, a vacuum of several pounds exists in the manifold when the engine is in operation. Consequently, as soon as the engine is started, the air will be exhausted from the part of the cylinder below the piston thus moving the piston 34 to the lower end of the

cylinder 32 and holding it in this position so long as the engine continues to run. A rubber or leather washer 35 may be used under the piston to seal the opening through 70 which the rod 36 slides when the piston is at the lower limit of its stroke. While the

engine is in operation, therefore, the connection between the thermostat 14 and the lever 18 will act exactly as though it were a continuous rod, as usually is employed in mechanisms of this type, and the thermostat there- 75 fore, will be enabled to exercise exactly the same control over the shutters 10 that it does in the present constructions. As soon,

however, as the engine is stopped, the partial 80 vacuum in the manifold 44 is relieved, or ceases to exist, and the spring 28 then acts through the lever 18 and the link 22 to close the shutters. The piston and cylinder ar- 85

angement affords no substantial resistance to this movement since the piston merely draws air through the manifold 44, the tube 42 and duct 40 into the cylinder 32. The range of travel of the piston in the cylinder preferably is sufficient to allow the complete 90 closing movement of the shutters even when the thermostat otherwise would hold them wide open. The shutters thus will be maintained in their closed positions until the engine is started again. If, in the mean- 95

time, the water circulating system is cooled off to a point below that at which the thermostat is set to effect an opening movement of the shutters, they will continue to remain in their closed positions until the system is warmed up sufficiently to cause the thermo- 100 stat to open them. If, on the other hand, the period in which the engine has been stopped is short, or if for any other reason the circulating water has not cooled off sub- 105

stantially, then the starting of the engine will result in setting the shutters again in substantially the position that they occupied when the engine was stopped. In other

words, the mechanism just described acts 110

automatically to release the shutters from the control of the thermostat as soon as the

engine is stopped and will restore the

shutters again to the control of the thermo-

stat as soon as the engine is started. 115

The arrangement shown in Fig. 3 differs from that shown in Figs. 1 and 2 merely in that the automatic operating mechanism for the shutters has been replaced by a hand operated mechanism. In this arrangement 120 the upper rod 30, corresponding to the rod 36 of the construction shown in Figs. 1 and 2, is connected to one arm of a bell crank lever fulcrumed on a part of the radiator casing. The other arm of this lever is piv- 125

oted to a hand operated rod 48 that projects through the dash 50 of the vehicle and is

provided with a knob by means of which it

may be manually adjusted to open or close 130

the shutters more or less. The lower side of

the rod is toothed to engage a projection 52 and a spring 54 tends to hold the rod in engagement with the part 52 in order to retain the rod in its adjusted position. The 5 same connection is provided, however, between the rods 30 and 36 that has been above described in connection with Figs. 1 and 2, so that the shutters are automatically released from the hand control and are automatically closed as soon as the engine is stopped, but are restored again to the hand control upon the starting of the engine.

While I have herein shown and described the best embodiment of the invention of 15 which I am at present aware, it will readily be understood that this embodiment may be modified in many particulars while still retaining the essential spirit or characteristics of the invention.

20 What is claimed as new is:

1. In combination with an engine and shutters for regulating the flow of air to cool said engine, spring means for actuating said shutter to closed position, actuating 25 means for actuating said shutters to open position, and a connecting member between said shutters and said actuating means, comprising a pair of axially disposed longitudinally movable rods and suction means 30 responsive to the running condition of the engine for connecting the same to move together.

2. In combination with an engine and shutters therefor to control the flow of air, a 35 shutter actuating device, and connecting members interposed between said actuating device and said shutters, said connecting members comprising a chamber having movable walls, one wall of said casing being fixed to move with said actuating device, and another wall of said casing being connected to move with said shutters, and means 40 to prevent relative movement of the walls.

3. In combination with an engine and 45 shutters therefor to control the flow of air, a shutter actuating device, resilient means biasing said shutter to closed position, and connecting members interposed between said actuating device and said shutter, said connecting 50 members comprising a chamber having movable walls, one wall of said chamber being fixed to move with said actuating device, and another wall of said chamber being connected to move with said shutters and means 55 to prevent relative movement of said walls.

4. In combination with an engine and 60 shutter therefor to control the flow of air, a shutter actuating device, connecting members interposed between said actuating device and said shutter, said connecting members comprising a telescoping chamber, one 65 part of said chamber being fixed to move with said actuating device, and another part of said chamber being connected to move

with said shutter and means for applying engine suction to the interior of said chamber.

5. In combination with an engine and shutter therefor to control the flow of air, 70 a shutter actuating device, resilient means biasing said shutter to closed position, and connecting members interposed between said actuating device and said shutter, said connecting members comprising a collapsible 75 casing member, one part of said casing being fixed to move with said actuating device, and another part of said casing being connected to move with said shutter and means for applying engine suction to the interior of 80 said casing.

6. In combination with an engine and shutters therefor, a shutter actuating device, a connecting member interposed between the actuating device and the shutters, said connecting member comprising a pair of rods disposed end to end, a cylinder carried by one of the contiguous ends of said rods, a piston carried by the other rod operating in said cylinder, and means for applying engine 90 suction to said cylinder to maintain the connecting member at a certain predetermined length during engine operation.

7. In combination with an engine and shutters therefor, a shutter actuating device, 95 a connecting member of variable length interposed between the actuating device and the shutter, said connecting member comprising a pair of elements disposed end to end, a cylinder carried by one of said elements, a piston carried by the other of said elements, said piston operating in said cylinder, means for applying engine suction to 100 said cylinder to give the connecting member a definite length when the engine is operating and spring means for changing the length 105 of said connecting member when the engine stops.

8. In combination with an engine and shutters therefor to control the flow of air, 110 a shutter actuating device, and connecting members interposed between said actuating device and said shutter, said connecting members comprising a cylinder and piston, one of which is connected to move with said shutters and the other located to move by said actuating device, and means to prevent 115 relative movement of the walls.

9. In combination with an engine and shutters therefor, a shutter actuating device, 120 a telescopic connecting member interposed between the shutters and the actuating device and means for utilizing power of the engine to determine the effective length of said connecting member.

10. In combination with an engine and shutters therefor, a shutter actuating device, 125 a telescopic connecting member interposed between the shutters and the actuating device, suction operated means included in said 130

connecting member for determining its effective length, and means for applying engine suction to said suction operated means.

11. In combination with an engine and shutters therefor to control the flow of air, a shutter actuating device, connecting members interposed between said actuating device and said shutter, said connecting members comprising a cylinder and piston, one of which is connected to move with said shutters and the other located to move by said actuating device and conduit means connecting the interior of said cylinder and piston with a source of engine pressure.

12. In combination with an engine and shutters therefor to control the flow of air, a radiator for said engine, a thermostat mounted in the upper end of said radiator, connecting means between said thermostat and said shutters comprising a telescoping casing having one part connected to move with said shutters and another part to move with said thermostat, and means responsive to the running condition of the engine to cause said parts to move together.

13. In a connecting device for radiator shutters and actuating devices therefor, a movable cylinder, a piston adapted to recip-

rocate in said cylinder, a connecting rod attached to said piston, and conduit means for connecting the interior of said cylinder to a source of pressure, whereby said piston and cylinder are made to move together.

14. In a connecting device for radiator shutters and actuating devices therefor, a casing having walls collapsible by reducing pressure therein, a connecting rod attached to move with one of said walls, a connecting rod adapted to move with the other of said walls, and a flexible conduit leading to the interior of said casing to connect the same with the source of pressure, whereby said piston and cylinder are made to move together.

15. In a connecting device for radiator shutters and actuating devices for the same, a telescoping chamber having one part connecting to move with a connecting rod, a second part connected to move with a second connecting rod and a flexible conduit leading to the interior of said chamber for connection to a source of suction, whereby said piston and cylinder are made to move together.

In testimony whereof I have signed my name to this specification.

FREDERICK M. FURBER.
